UNITED STATES PATENT OFFICE.

HYMAN FREEDMAN AND NATHAN M. FREEDMAN, OF CHICAGO, ILLINOIS, ASSIGNEES
TO DAVOPLANE BED COMPANY, A CORPORATION OF ILLINOIS.

DAVENPORT-BED STRUCTURE.

Original application filed May 15, 1916, Serial No. 97,688. Divided and this application filed March 6, 1919. Serial No. 280,964.

To all whom it may concern:

Be it known that we, HYMAN FREEDMAN and NATHAN M. FREEDMAN, citizens of the United States of America, and residents of 5 Chicago, county of Cook, and State of Illinois, have invented certain new and useful Improvements in Davenport-Bed Structures, of which the following is a specification.

10 Our present invention has relation to improvements in bed structures, and more particularly to bed structures capable of being folded and adapted to be installed within davenports and sofas, whereby the piece 15 of furniture may be used in folded position as a davenport or sofa, and may be unfolded to form a bed. The subject matter of this invention is disclosed in our copending application, Serial No. 97,688, which was allowed 20 January 24, 1919, and which is directed to the means shown for hinging the bed bottom to the front part of the sofa frame.

The principal object of our present improvement is to provide an improved form 25 of sofa bed capable of more compact storage of the bed; to provide an improved form or pivot joint for securing the seat to the front part of the sofa frame; and furthermore to 30 provide a structure of maximum sturdiness and dependability. This latter object, as will be hereafter seen, is largely accomplished by providing a structure in which the main supporting standards which carry 35 the bed may be attached to and carried by the main sofa or davenport frame structure, instead of to the hinging portion of the seat of the sofa or davenport. We believe that this has not heretofore been done without 40 materially lessening the size of bed which could be installed in a sofa or davenport of a given size.

We attain the above objects by means of the structure illustrated in the accompanying drawing, in which—

45 Fig. 1 is an end elevation of a sofa or davenport, the near end being cut away, and our bed structure being installed therein and being shown in fully extended or open 50 position.

Fig. 2 is a plan of the structure shown in Fig. 3.

Fig. 3 is an elevation of a fragment of our bed structure, showing the means for hing-

ing the hinged portion of the sofa seat and 55 the means for hinging the inner and adjacent sections of the bed structure and the main mounting or means for securing the bed to the sofa or davenport.

The sofa or davenport, in which our bed 60 structure is installed, consists of a back 1 and sides 2 secured to said back and extending forwardly therefrom. The sides 2 may be, and generally are, extended sufficiently 65 above the seat to form the usual arms. In view of the fact that with our present form 70 of bed it is only necessary to hinge the top of the seat (distinguishing for instance from a rotary seat), a substantial front board 3 may be employed to rigidly connect the 75 forward ends of the sides 2 and thereby secure a much stronger main davenport sofa structure.

The hinged portion of the seat 4, which 80 is shown in Fig. 1 in open position, is secured to the main portion of the davenport or sofa structure by the U-shaped links 5, 85 the ends whereof are respectively pivoted to the forward inner ends of the sides 2 and the sides of the hinged portion of the seat 4. The links 5 are given the U-shaped form 90 to permit their ends to be secured below the respective edges of the parts to which they are attached, as viewed in Fig. 1, and also to provide room for upholstery upon the 95 forward portion of the hinged portion of the seat, should that be desired.

The forward ends of the links 5 are provided with an extension 6 to which is pivoted a link 7, the opposite end of which is pivoted to a leg 8, the upper end of which leg is pivotally carried by a bracket 8^a mounted upon the end of the movable seat member opposite the hinge 5 so that when the hinged portion of the seat 4 is opened 100 up, the leg 8 is extended to support the structure in open position, and when the hinged portion of the seat 4 is folded into closed position, the leg 8 is folded beside the same.

Supplementing the links 5 as a means of connecting the hinged portion of the seat 4 with the main portion of the sofa or davenport structure, are the links 9, the forward ends of which are pivoted to laterally projecting pins 10 extending from plates 11 secured to the sides of the hinged portion 4 of the seat. The rearwardly extending por-

tion of each link 9 has a horizontally extending flange 12 which slides upon a longitudinally slotted plate 13 secured to the main sofa or davenport structure, and the links 9 are secured to their respective plates 13 by means of headed pins 12^a, which extend through the slots in the said plates. It will be seen that the addition of the sliding and pivoting links 9 to the U-shaped links 5 secures a stronger, smoother, and superior connection between the hinged portion 4 of the seat and the main davenport or sofa structure.

The folding bed frame structure consists of a plurality of large or main sections and one or more small connecting sections, the head and foot sections or outside sections of which are each formed of a side rail 14 and end rails 15, 15. When an intermediate large frame section is employed, it consists of end rails 15^a only.

The end rails of the respective large frame sections are preferably united by pivoting the adjacent ends to links 16 and 17 which constitute short frame sections. This construction is employed for the purpose of securing space between the large sections when folded so as to house the bedding.

Extending upwardly from near the ends of the front board 3 are standards 18 to the tops of which are pivoted the ends of the plates or brackets 19, to the opposite ends of which plates are rigidly secured the end rails 15^a of the intermediate bed section, if three bed sections be employed, or the end rails 15 of the outer section if but two bed sections be employed. As will be clearly seen, this bracket 19 is L-shaped and includes an offset portion or short-arm to which the connecting pivot is secured, so that said bracket throws the intermediate or outer section, whichever may be secured to it, further out when the bed is unfolded, and permits the employment of a larger bed structure for a given size of sofa or davenport, said portion or arm being disposed toward the short section 16 or rearward when the device is unfolded.

The inner section of the bed is preferably secured to the sofa or davenport structure by means of links 20 pivoted respectively to a bracket 20^a mounted upon the sofa or davenport structure and to the end rail 15 of the inner bed section. A spring 21 is employed which serves to ease the action of the bed in reaching fully open position and to assist when closing the structure is commenced.

The intermediate large section, when three large sections of bed are employed, or the outer section when but two large sections are used, is secured to the hinged portion 4 of the seat by the links 22 pivoted to the end rail of the section and having a slot 23 in the other end thereof through which ex-

tends a headed pin 24 projecting from the side of the hinged portion 4 of the seat.

When three large sections of the bed are employed, it is desirable to employ a transverse brace 25 between the hinge links 17, and we have found it desirable also to provide an additional leg 26 pivoted at its upper end to the outer portion of the outer end rail. This leg is automatically operated by a link 27 connecting the same to the forward end of the hinge plate 17. Also when a bed of three sections is employed, it is desirable to provide a latch 28 for securing the outer section upon the intermediate section when these sections are folded together, so that they may both be folded upon the inner section.

Although but one specific embodiment of this invention has been herein shown and described, it will be understood that numerous details of the construction shown may be altered or omitted without departing from the spirit of this invention as defined by the following claims.

We claim:

1. In a davenport comprising a main frame having sides the ends of which are respectively rigidly connected by a back and front, a movable seat, and means for hinging said seat to said front consisting of a U-shaped link the ends whereof are respectively connected to said front and seat, in combination with a separate link having a pivotal connection with one of said members and a sliding connection with the other of said members.

2. In a davenport comprising a main frame having sides the ends of which are respectively rigidly connected by a back and front, a movable seat, and means for hinging said seat to said front consisting of a U-shaped link the ends whereof are respectively connected to said front and seat, in combination with a separate link having a pivotal connection with said seat and a sliding connection with said main frame.

3. In a davenport, a main frame, a movable seat, and means for hinging the seat to the front of the frame comprising a plate secured at the end of the seat adjacent the lower front edge thereof, a link pivoted at its ends to said plate and to the frame at the adjacent edges of the frame and seat and having an intermediate offset portion which adapts the seat to be projected forwardly from the frame when the seat is overturned, together with a separate link having a pivotal connection with the plate and a slidable connection with the frame.

Signed at Chicago this 28th day of Feb. 1919.

HYMAN FREEDMAN.
NATHAN M. FREEDMAN.
